Primary Examiner — Joseph Kukella(74) *Attorney, Agent, or Firm* — Perkins Coie LLP(57) **CLAIM**

The ornamental design for a signal light for a loading dock, as shown and described.

DESCRIPTION

FIG. 1 is a front right top perspective view of a signal light for a loading dock showing an embodiment of our new design;

FIG. 2 is a front right bottom perspective view thereof;
FIG. 3 is a front elevation view thereof;

FIG. 4 is a right side elevation view thereof, the left side elevation view being a mirror image of the right side elevation view;

FIG. 5 is a top plan view thereof;

FIG. 6 is a bottom plan view thereof; and,

FIG. 7 is a rear elevation view thereof.

The dash-dash broken lines shown in the figures represent portions of the signal light for a loading dock that form no part of the claimed design. The dot-dash broken lines shown in the figures define the bounds of the claimed design and form no part thereof.
